UNITED STATES PATENT OFFICE.

BROR A. M. MUNSON, OF BROOKLYN, NEW YORK.

DESIGN FOR A GAME-BOARD.

51,755.

Specification for Design.

Patented Feb. 12, 1918.

Application filed December 10, 1917. Serial No. 206,558. Term of patent 7 years.

To all whom it may concern:

Be it known that I, BROR A. M. MUNSON, a subject of the King of Sweden, and a resident of Brooklyn, in the county of Kings and State of New York, have invented a new, original, and ornamental Design for a Game-Board, of which the following is a specification, reference being had to the accompanying drawing, forming part thereof.

The figure is a plan view of a game board showing my new design.

I claim—

The ornamental design for a game board as shown.

BROR A. M. MUNSON. [L.S.]
